UNITED STATES PATENT OFFICE.

HENRY PRICE BALL, OF PITTSFIELD, MASSACHUSETTS, ASSIGNOR TO GENERAL ELECTRIC COMPANY, A CORPORATION OF NEW YORK.

ELECTRIC FLAT-IRON.

1,132,299.

Specification of Letters Patent. Patented Mar. 16, 1915.

Application filed June 23, 1913. Serial No. 775,214.

To all whom it may concern:

Be it known that I, HENRY PRICE BALL, a citizen of the United States, residing at Pittsfield, county of Berkshire, State of Massachusetts, have invented certain new and useful Improvements in Electric Flat-Irons, of which the following is a specification.

My invention relates to electric flat-irons and more particularly to means for controlling the supply of electric energy thereto.

Flat-irons are usually made with a pair of projecting contacts carried by the body thereof and connected with the resistance element, the contacts being adapted to receive a plug carrying circuit terminals. This plug engages the contacts with considerable friction and is therefore not readily removed or replaced. It is often desirable to cut off the current at the iron temporarily and as it is inconvenient and awkward to remove the plug it has been proposed as a convenient means to provide a separate circuit controller, as a snap switch, on the iron for this purpose. These switches have not been wholly satisfactory, however, in that they add additional parts to the iron, get out of order easily, and also add materially to the cost of manufacture. These switches have also been found objectionable in that they are not readily accessible, it being necessary for the operator to either place the iron on the stand and remove his hand from the handle to manipulate the switch, or to hold the iron in one hand and manipulate the switch with the other.

By my invention it is proposed to provide a combined plug and switch, the plug being arranged to detachably engage the flat-iron and to be oscillated into and out of position for closing the circuit.

A further object of my invention is to so locate the operating means for my combined switch and plug that it may be readily operated by a single movement of the hand of the operator without removing the hand from the handle of the iron.

The invention comprises various features of novelty and combinations of parts all of which will be fully explained hereinafter and pointed out in the claims.

In the drawings, Figure 1 is a perspective view of a flat-iron with my improved plug switch attached thereto. Fig. 2 is a face view of the plug switch showing the line 55 terminals. Fig. 3 is a section on line 3—3, Fig. 2. Fig. 4 is a face view similar to Fig. 2 but with the contacts and insulating member removed in order to illustrate certain details of structure. Fig. 5 is a longitudinal 60 view of the elements of the switch carried by the iron. Fig. 6 is a face view showing the contact elements which are mounted on the iron and taken substantially on line 6—6, Fig. 5. Fig. 7 is a detail section taken 65 on line 7—7, Fig. 1.

Referring to the drawing 1 indicates the base of an electrically heated flat-iron which may be of ordinary construction, and 2 the handle thereof. The handle is shown as 70 being supported by two braces 3 and 4. Attached to the rear brace 4 is a conduit 5 through which the contact terminals 6 and 7 from the heater element extend. These terminals are shown as flat metallic strips having their ends bent at right angles to engage with the contact plates 8 and 9 which plates are suitably fastened to the mica insulation 10, and are exposed in position to coöperate with contacts carried by the plug switch as 75 80 will be described hereinafter. The contact terminals 6 and 7 are embedded in suitable insulating material as will be clear from the drawing.

11 and 12 designate wear plates which 85 may be made of metal or insulating material and which are suitably attached to the insulation 10, as for instance, by means of screws 13.

The handle 2 is hollowed out as shown 90 more particularly in Fig. 5, and located within this hollow portion are two parallel strips 14 connected at their ends as at 15. These two strips are preferably made of one continuous piece of material reversely bent 95 upon itself as is clearly shown in Fig. 5. Engaging the connecting member 15 is a screw bolt 16 which extends in from the front of the handle through the brace 3 for holding the respective parts in place. The 100 parallel strips 14 are provided with oppositely disposed longitudinal slots 17, in

which slots ride the projecting lugs 18 of a threaded nut 19.

20 is a shaft threaded at one end for engagement with the nut 19 and carrying at its opposite end the rollers 21 and 22, as more clearly shown in Fig. 7. Surrounding this shaft 20 is a compression spring 23 located between the nut 19 and a fixed abutment 24. The shaft 20 projects beyond the rear of the handle and engages the embossed portion 25 of a circular head 26 carried by the stand 27. This stand 27 is made of spring metal and tends to force the shaft 20 to the left as shown in Fig. 5. Located on the shaft 20 between the handle and the end of the shaft is a spacing sleeve 28 which holds in place a cup-shaped member 29 having a serrated edge 30. The rollers 21 and 22 carried by the shaft 20 are arranged to ride on this serrated edge and are held yieldingly in engagement therewith by spring 23 and spring stand 27. This cup-shaped member 29 is loose on shaft 20 and carries a lug 31 for a purpose which will presently be described. The plug switch consists of a casing 32 having spaced therefrom an inner wall 33. Between these two walls is located an irregularly shaped member 34 having an opening 35 and two recesses 36 and 37. Attached to this member 34 and passing through a slot 38 in the top of casing 32 is a projecting operating arm 39 the outer end of which is angularly bent and attached to a guide 40 through which the electric lead wire 41 and 42 pass. The opening 35 and slot 38 are of such a width as to permit of a slight amount of lost motion on the part of arm 39. A coiled spring 43 surrounds and protects the lead wires between the guide and the plug.

A block of insulating material 44 carrying the line terminals 45 and 46 is located in the casing 32 and is held in place by screws 47 which take into the outer wall of the casing. These screws pass through and hold in place spacing sleeves 48 for spacing the inner wall 33 from the outer wall of the casing, the upper central spacing sleeve being located in opening 35 and adapted to be engaged by the opposite edges thereof for oscillating the plug when in place on the iron. The plug is slotted as shown at 49 and is adapted to be inserted in the space between the rear of the handle and the member 29, the slotted portion taking over the spacing sleeve 28 and also the lug 31 as clearly shown in Fig. 4. The plug fits tightly in this space and will be firmly held by the action of the spring 23 and spring stand 27 the same being placed under a slight tension when the plug is inserted. The plug is thus held in position on the sleeve 28 and lug 31 simply by the friction caused by the spring 23 and spring stand 27, and the plug is thus freely detachable therefrom.

The operation of my improved switch plug is as follows: Assuming that the plug is detached from the iron and it is desired to use the same, the plug will be forced into place, the slotted portion thereof fitting over the sleeve 28 and lug 31. This insertion should be made with the handle of the plug substantially vertical and if desired suitable guides (not shown) might be provided whereby the plug could only be inserted and removed when in such position. It will be noted that when the plug is so inserted that the contacts 45 and 46 will lie in a plane at right angles to the plane of terminals 8 and 9 and in engagement with wear pieces 12 and 13. To bring the contacts into engagement it is therefore necessary to oscillate the plug either to the right or the left. In order to do this the guide 40 is forced in either direction carrying with it the operating arm 39. The operating arm having a slight amount of lost motion the first movement thereof causes the parts to assume the position as shown in dotted lines in Fig. 4. Further movement of the arm will now tend to force the plug to oscillate owing to the edge of opening 35 in member 34 engaging with the central spacing sleeve 48. The movement of the plug is retarded however by the fact that cup shaped member 34 to which lug 31 is attached must also be oscillated along with the plug, and in order to oscillate this member 34 it is necessary to force the rollers 21 and 22 up an inclined plane of the serrated edge 30. As the rollers pass up the inclined edge the spring 23 and spring stand 27 are put under still greater tension and as soon as the rollers pass beyond the top of the plane will snap the same quickly down the opposite incline and thereby bring the contacts into engagement with a snap action, the lost motion before described permitting the plug to move independently of the operating arm 39. To open the contacts the operation is the same only in an opposite direction.

It is clear that I may so design my switch plug and the coöperating cup-shaped member 29 that a movement over one serration may represent an angular movement of 90° or a movement somewhat less than 90° it being only necessary that the movement be sufficient to properly separate the contacts. In actual practice I have found an angular movement of 60° to be satisfactory and hence when the contacts are separated the operating arm stands at an angle of 30° to the vertical either upon one side or the other. This is the arrangement I have illustrated.

By means of arranging the switch plug so that the operating movement may be wholly upon the right-hand side or the left-hand side of the iron I peculiarly adapt the same to the use of either a right-handed or

left-handed person, it being obvious that a left-handed person would require an opposite arrangement of switch to that which would be required by a right-handed person.

5 The location of the operating arm is described is such that it does not interfere with the ironing operation and makes it readily accessible without removing the hand from the iron for quickly controlling 10 the supply of energy.

What I claim as new and desire to secure by Letters Patent, is:—

1. The combination with an electric flat-iron having contact terminals thereon, of 15 a member carrying contact terminals having frictional engagement with a part of the said flat-iron so that the member is freely detachable therefrom, said member being movable on said flat-iron to bring the respective terminals into and out of engagement, and means whereby said movement into and out of engagement is made with a snap action.

2. The combination with an electric flat-iron having contact terminals thereon and a supporting pivot associated therewith, of 20 a member carrying contact terminals and adapted to removably engage said pivot and oscillate thereon to bring the respective terminals into and out of engagement, and means whereby said oscillation into and out of engagement is made with a snap action.

3. The combination with an electric flat-iron having contact terminals thereon, of a 25 member having frictional engagement with a part of the said flat-iron so that the member is freely detachable therefrom, terminals carried by said member, said member being movable on the iron in more than one direction to bring the respective terminals into and out of engagement.

4. The combination with an electric flat-iron having contact terminals thereon and a supporting pivot associated therewith, of 45 a member carrying contact terminals and frictionally held in engagement with said pivot and adapted to oscillate in either of two directions thereon to bring the terminals into and out of engagement.

5. The combination with an electric flat-iron having contact terminals thereon, of a member detachably engaging said flat-iron, terminals carried by said member, said member being movable in either of two directions on said flat-iron to bring the respective terminals into and out of engagement, and means whereby said movement into and out of engagement is produced with a snap action.

6. The combination with an electric flat-iron having contact terminals thereon and a horizontally disposed pivot associated therewith, of a member carrying contact terminals and frictionally held in engagement 60 with said pivot whereby said member is

freely detachable from the pivot, said member being adapted to oscillate on the pivot to bring the respective terminals into and out of engagement.

7. The combination with an electric flat-iron having contact terminals thereon and a horizontally disposed pivot associated therewith, of a member carrying contact terminals and adapted to removably engage said pivot and oscillate thereon to 75 bring the terminals into and out of engagement, and means whereby said engagement and disengagement is made with a snap action.

8. The combination with an electric flat-iron having contact terminals thereon and a horizontally disposed pivot associated therewith, of a member carrying contact terminals and frictionally held in engagement with said pivot whereby said member 80 is freely detachable from the pivot, said member being adapted to oscillate in either of two directions on said pivot to bring the respective terminals into and out of engagement.

9. The combination with an electric flat-iron having contact terminals thereon and a horizontally disposed pivot associated therewith, of a member frictionally held in engagement on said pivot whereby the member 85 is freely detachable therefrom, said member being adapted to oscillate in a vertical plane, and contact terminals carried by said member.

10. The combination with an electric flat-iron having contact terminals thereon and a horizontally disposed pivot associated therewith, of a member frictionally held in engagement on said pivot whereby the member 100 is freely detachable therefrom, said member being adapted to oscillate in a vertical plane, contacts carried by said member, and a projecting handle for oscillating said member.

11. The combination with an electric flat-iron having contact terminals thereon and a horizontally disposed pivot associated therewith, of a member mounted on said pivot to oscillate in a vertical plane, contact terminals carried by said member, a projecting handle for oscillating said member, and means for causing said terminals to engage 110 and disengage with a snap action.

12. The combination with an electric flat-iron having contact terminals thereon, of a member having an operating handle and carrying contact terminals and adapted to pivotally engage said iron with the handle upon either side of the vertical plane through the center of the iron and oscillatable wholly upon such side to bring the terminals into and out of engagement.

13. The combination of an electric flat-iron having contact terminals thereon, a member carrying terminals arranged to en- 125 130

gage the first-named terminals, said member being frictionally held in engagement with a part of said flat-iron whereby the member may be freely detached therefrom, 5 and means for moving the terminals of said member into and out of engagement with the flat-iron terminals with a snap action.

In witness whereof, I have hereunto set my hand this 19th day of June 1913.

HENRY PRICE BALL.
